Primary Examiner — Richard Kearney*Assistant Examiner* — Michael Hoffman(74) *Attorney, Agent, or Firm* — Charles F. Reidelbach, Jr.(57) **CLAIM**

The ornamental design for a tube securing device latch, as shown and described.

DESCRIPTION

FIG. 1 is a front, top, and right side perspective view of a tube securing device latch showing our new design;

FIG. 2 is a front elevational view thereof;

FIG. 3 is a rear elevational view thereof;

FIG. 4 is a front and right side perspective view thereof;

FIG. 5 is a front and left side perspective view thereof;

FIG. 6 is a top plan view thereof; and,

FIG. 7 is a bottom plan view thereof.

The broken lines shown in the drawings illustrate environmental structure and form no part of the claimed design.
